A. A. Johnson Inventor

United States Patent Office.

ASA JOHNSON, OF BROOKLYN, NEW YORK.

Letters Patent No. 82,323, dated September 22, 1868; antedated September 11, 1868.

IMPROVEMENT IN NECK-TIES.

The Schedule referred to in these Letters Patent and making part of the same.

TO ALL WHOM IT MAY CONCERN:

Be it known that I, ASA JOHNSON, of Brooklyn, in the county of Kings, and State of New York, have invented a new and improved Neck-Tie; and I do declare that the following is a full and exact description thereof, reference being had to the accompanying drawings, and to the letters of reference marked thereon.

Figure 1 is a perspective view of the neck-tie.

Figure 2 is an elevation of a bow or "butterfly" with retainer attached.

Figure 3 is an enlarged view of the material used.

Figure 4 is a view of a section of a neck-tie, showing the material cut bias to form the end.

My invention consists in making neck-ties out of wire cloth or gauze, or of a material when warp or weft is composed wholly or in part of wire.

To enable others skilled in the art to make and use my invention, I will proceed to describe my method of carrying out the same.

In making my neck-ties, I use wire cloth or gauze, woven in figures or plain, and either colored, or not, over a whole or a portion of its surface. It may be woven in stripes or figures, and wire of different colors and of different material may be used; or part wire and part textile material may be used to form the stripes or figures. Instead of depending upon coloring the wire to produce ornamental effects, stripes or figures may be stamped, or worked upon the plain wire cloth with a needle.

In forming this article, as shown in figs. 3 and 4, it is cut so that its edges may be doubled or folded over, the divided edges meeting on the back and soldered together, as seen in figs. 4 and 5.

It is obvious that neck-ties may be made in any shape, and secured to the person in any of the known forms, without departing from the principle of my invention.

In preparing wire for weaving different stripes and figures, any or every known metal may be used, and compounded in such proportions as to give any quality of metal or shade of colors desired. Then, from those different kinds or compositions of metal, wires may be drawn of different colors, and any number of them may be twisted or melted together in such a manner as to give any number and kinds of colors desired; or a mixture of small pieces, of various shapes and sizes, of these wires or kinds, and colored metals, may be melted together, in such a manner as to form, when cold, a solid mass, showing separate and distinctly all the various colors of which the mass is composed. Then a wire may be drawn from any or all of the above-described wires or compositions of metals, and these last-mentioned wires may be ornamented, in any manner desired, by passing the wire through between rollers or dies formed for that purpose, with grooves or indentations made therein, thereby making the impressions so deeply into the metal that they will not wear off; or the wire may be plated with silver or gold, or colored with any or every other metallic or mineral substance, thus imparting a great variety of durable colors. If desirable, the figures may be stamped or painted after the cloth is woven, the same as cotton or woollen fabrics are now painted or stamped.

Therefore, by weaving a cloth of a variety of these different shapes and kinds of wires, either single, or two or more twisted together, a great variety of designs and handsome and durable figures may be formed; and by using only such metals as gold, platinum, silver, and such other metals or composition of metals that will not corrode, a very beautiful and durable cloth may be formed, a cloth that neither acid, grease, nor dirt of any kind will injure.

The advantages of neck-ties made of this material are, that they are cheap, easily cleaned, and very durable, and may be left open, too, for purposes of ventilation in summer, or painted, varnished, or lined, to make them warm for winter, and when made of gold or other valuable metals, they are valuable, when worn out, for old metal, the edges of the wire cloth being rendered smooth and kept from ravelling by being tinned.

The parts of neck-ties made separate, may be joined together by soldering or by sewing with thread or small wire.

What I claim, and desire to secure by Letters Patent, is—

A neck-tie formed of wire cloth or gauze, substantially as described, as a new article of manufacture.

ASA JOHNSON.
